UNITED STATES PATENT OFFICE

107,489

DESIGN FOR A TEXTILE FABRIC

Jacques E. Maisch, New York, N. Y., assignor to National Fabrics Corporation, New York, N. Y., a corporation of Delaware

Application September 11, 1937, Serial No. 71,569

Term of patent 3½ years

To all whom it may concern:

Be it known that I, Jacques E. Maisch, a citizen of the Republic of France, residing at New York, N. Y., in the city, county, and State of New York, have invented a new, original, and ornamental Design for a Textile Fabric, of which the following is a specification, reference being had to the accompanying drawing, forming part thereof, wherein—

The figure is a plan view of a textile fabric showing my new design, with a unit of design outlined in dot and dash lines.

I claim:

The ornamental design for a textile fabric substantially as shown and described.

JACQUES E. MAISCH.
